UNITED STATES PATENT OFFICE.

CHARLES H. CHAPMAN, OF SHIRLEY, ASSIGNOR OF ONE-HALF OF HIS
RIGHT TO LEVI WALLACE, OF AYER, MASSACHUSETTS.

SPINDLE AND THE METHOD OF LUBRICATING THE SAME.

SPECIFICATION forming part of Letters Patent No. 233,474, dated October 19, 1880.

Application filed January 30, 1880.

To all whom it may concern:

Be it known that I, CHARLES H. CHAPMAN, of Shirley, in the county of Middlesex and State of Massachusetts, have invented certain 5 Improvements in Spindles and in the Method of Lubricating the Same, of which the following is a specification.

This invention has for its object to provide certain improvements in spindles, whereby 10 sliding such spindles longitudinally on their standards, as in the operation of doffing the bobbins, will, by a pump-like or vacuum action, cause an upward flow of oil from a reservoir to lubricate the bearing-surfaces of the spindle 15 and the fixed standard on which it rotates.

My invention consists in the improvements which I will now proceed to describe and claim.

In the accompanying drawings illustrating my invention, Figure 1 represents a longitudinal vertical section of a live-spindle and its 20 support embodying my improvements; Fig. 2, a similar view, showing the spindle raised; and Fig. 3, a section on line $x-x$ of Fig. 1.

The same letters of reference are used to indicate like parts in all the figures.

In carrying out my invention I provide a fixed standard, a , rising from a cylindrical base, b , which is suitably attached to the rail c of a spinning-machine, and is chambered out 30 around the standard a to form an oil-reservoir, d . The standard a has a longitudinal groove or channel, e , extending from its lower to its upper end, and is provided with an oil-cup, B , at its upper end.

35 f represents the live-spindle, which is socketed in the oil-cup B of the standard, and its lower end extends below the whirl i and projects into the oil-reservoir d , nearly to the bottom thereof, when in its normal position, as 40 seen in Fig. 1, the said oil-reservoir being rather deeper and the live-spindle rather longer than usual. The spindle is provided with a step, f' , having an oval or rounded end fitting into a socket in the end of the standard a , 45 said socket being composed of a ring or tube, P , preferably to steady the step f' laterally. The lower end of the step or pivot f' rests on a hardened-steel plate or bearing, R , the ring P and bearing R being held in a socket in the

standard a , the upper part of said socket forming the oil-cup B . 50

By this construction of spindle-bearing the spindle is caused to run with but little friction as compared with the usual V-shaped step and bearing. 55

The ring P may be omitted, and the oil-cup B may extend entirely down to the bearing R .

The oil-cup always contains oil enough to lubricate the step f' , as will presently appear.

The cylindrical base b is provided with a 60 screw-cap, g , which covers the top of the oil-reservoir, and is constructed so as to form an outside bearing, h , which surrounds and fits snugly against the lower portion of the spindle f below the whirl, and assists in steadyng the 65 spindle and preventing it from vibrating when rotating rapidly, said outside bearing being preferably an externally-threaded brass sleeve screwed into the cap g .

The spindle f is movable longitudinally on 70 the standard a , and its upward movement is limited by a stop, j , formed on or near its lower end, which stop abuts against the cap g when the spindle is raised, as shown in Fig. 2.

It will be seen that when the spindle is raised 75 the upper end of its socket, which receives the standard a , will be raised above the upper end of said standard, thereby forming a space, k , which is practically a vacuum, and can only be filled by way of the groove or channel e , 80 the socket of the spindle having no opening excepting at its lower end. It follows, therefore, that an upward flow of oil through the groove e will be induced by atmospheric pressure or pump-like action, so that the space k 85 will be instantly filled with oil, and when the spindle is allowed to descend all the oil, excepting that in the oil-cup B , will be pressed downwardly through the groove, e , and the interstice between the bearing-surfaces of the 90 standard and spindle, thereby effectually lubricating said bearing-surfaces, the oil not consumed in lubricating returning to the reservoir.

In practice the described upward movement 95 of the spindle is effected by the act of doffing the bobbin or raising the bobbin from the spindle for any cause, the bobbin sticking so closely

to the spindle that both will move together when the bobbin is lifted until the movement of the spindle is arrested by its stop *j* abutting against the cap *g*, as described. The constant lubrication of the bearing-surfaces is therefore insured, the lubrication being practically automatic.

Oil is supplied to the reservoir through orifices *l l* in the cap *g*, said orifices being surrounded by a flange, *h'*, which permits a quantity of oil to accumulate above the cap and pass from thence into the reservoir. These orifices also supply air to the reservoir to take the place of the oil raised by atmospheric pressure. The whirl *i* is provided with a downwardly-projecting flange, *m*, which protects the cap *g* from dust when the spindle is in its normal position, Fig. 1.

I do not limit myself to the formation of a vacuum at the top of the standard *a* by raising the spindle, as the same result may be produced by depressing the standard without moving the spindle, and to this end several standards may be moved simultaneously by suitable mechanism operated by an attendant whenever it is desirable to lubricate the spindles.

I am aware that it has been proposed to construct a spindle with a grooved standard and a tube or shell surrounding and inclosing such standard, the two forming a dead-spindle to receive a live-spindle, and providing a bearing for such live-spindle in the upper end of the standard, to which oil is supplied by a fountain containing a column of oil acting upon the known principle of hydrostatic pressure.

I am also aware that a dead-spindle has been made with a circumferential spiral groove and an internal passage communicating with an oil-reservoir, and that to oil the live-spindle bearing at the top of the dead-spindle the

rotation of the live-spindle is depended upon to force the oil up the spiral groove, whence it returns to the oil-reservoir through the internal passage in the dead-spindle, maintaining, 45 as it were, a constant circulation; but I am not aware that before my invention a grooved dead-spindle or standard and a surrounding live-spindle of ordinary construction were so arranged as to admit of lubrication by atmospheric pressure after the manner of a pump or vacuum.

What I claim is—

1. The combination, substantially as set forth, of an oil-reservoir, a cap therefor, a standard rising from within said reservoir, a bearing on said standard for the spindle, a spindle supported in said bearing and movable longitudinally with relation to said standard to form a vacuum above the standard, 60 causing an upward flow of oil from the reservoir, and a stop, *j*, on said spindle, acting in conjunction with the cap to limit the movement of the spindle, as specified.

2. That improvement in the art of oiling 65 spindles of the class having an oil-reservoir, a grooved standard, and a live-spindle supported upon such standard which consists in raising the oil from the reservoir to the bearing-surfaces of the spindle by atmospheric pressure 70 superinduced by a longitudinal sliding motion of the live-spindle on the standard consequent upon doffing the bobbin, substantially as described.

In testimony whereof I have signed my name 75 to this specification, in the presence of two subscribing witnesses, this 21st day of January, A. D. 1880.

CHARLES H. CHAPMAN.
